UNITED STATES PATENT OFFICE.

LOTHAR W. FABER, OF NEW YORK, AND WILLIAM ROBINSON, OF BROOKLYN, NEW YORK, ASSIGNORS TO EBERHARD FABER PENCIL COMPANY, A CORPORATION OF NEW YORK.

PENCIL.

Application filed April 20, 1921. Serial No. 462,882.

To all whom it may concern:

Be it known that we, LOTHAR W. FABER, and WILLIAM ROBINSON, both citizens of the United States, and residents, respectively, of New York city, in the county of New York and State of New York, and Brooklyn, in the county of Kings and State of New York, have invented new and useful Improvements in Pencils, of which the following is a specification.

This invention relates to pencils of the type which comprise a casing to hold a length of lead at one end thereof and mechanism for ejecting or propelling said lead outwardly from said casing into operative writing position as the lead wears away or becomes broken off.

The objects of the invention are to provide a pencil of the character described embodying novel features of construction for holding and guiding the lead in the casing; to provide improved means for ejecting or propelling the lead from the casing; to provide a pencil of this character including a casing and a lead holding and guiding tube, and improved means for securing said lead holding tube in said casing; to thus provide a casing having a removable tip connected to one end thereof, and a lead holding tube with means for frictionally and adjustably mounting said lead holding tube in said tip; to secure the lead holding tube in said tip by means of a pair of complementary substantially cross-sectionally semi-circular strips of yielding frictional material, such as wood, applied to said tube from opposite sides thereof and frictionally forced into one end of said tip; to provide a casing formed of two telescoping correspondingly threaded tubes or sleeves one end of one of which is provided with a lead guiding passage, an ejecting rod being slidably mounted in said lead guiding passage, and the other of said sleeves being provided with a plug intermediate its ends to frictionally and detachably engage one end of said ejecting rod, whereby relative revolving of said sleeves in one direction causes relative longitudinal movement thereof to actuate the ejecting rod and propel the lead outwardly of said casing; to provide such a pencil which is simple and inexpensive in construction, and to obtain other results and advantages as may be brought out by the following description.

Referring to the accompanying drawings,

in which like numerals of reference indicate the same parts throughout the several views,

Figure 1 is a longitudinal sectional view through a pencil constructed in accordance with our invention;

Figure 2 is a side elevation of the pencil;

Figure 3 is a detached side elevation of the lead holding and guiding tube with the friction strips applied thereto;

Figure 4 is a detached side elevation of the barrel or casing of the pencil;

Figure 5 is a detached side elevation of the tip of the pencil;

Figure 6 is a similar view of the ejecting rod actuating sleeve;

Figure 7 is a side elevation of the cap of the pencil which serves as a closure for the reserve lead chamber;

Figure 8 is a perspective view of the lead holding and guiding tube and the friction strips detached therefrom;

Figure 9 is a perspective view of the lead ejecting rod, and

Figure 10 is a perspective view of the lead holding tube, friction strips and the ejecting rod assembled.

In the embodiment of our invention shown in the drawings the reference character 1 designates the main barrel or casing of the pencil which is tubular in formation and has threads 2 rolled therein and extending from one end thereof to a point adjacent to the opposite end. A tubular tip 3 has one end thereof threaded as at 4 and is adapted to be screwed into one end of the main barrel 1, the walls of said tip at the opposite end thereof tapering as indicated at 5. The tip 3 is adapted to receive a lead holding and guiding tube 6 which is of a diameter 80 slightly greater than the opening at the small end of the tip and has one end tapered as indicated at 7 and slit for a portion of its length as at 8, said end being adapted to pass through the opening on the small end 100 of the tip 3 as shown in Fig. 1.

The lead holding tube 6 is frictionally and adjustably mounted in the tip 3, and when the tube is forced outwardly through the small end of the tip as indicated in Fig. 1, the walls of the tip engaging the tapered and split end 7 of the tube forces the same into tight frictional engagement with the lead 9 which is slidably mounted in the tube 6 so as to hold the lead against falling out of

the tube 6. For the purpose of mounting the lead holding tube 6 in the tip 3 we preferably form the tube with spaced projections 10 on the exterior thereof and provide 5 a pair of complementary strips 11 substantially semi-circular in cross-section and formed of a yielding frictional material, such for instance as wood, the said strips 11 being applied to the tube 6 from opposite 10 sides thereof over the projections 10. The diameter of the strips 11 is slightly greater than the internal diameter of the threaded end 4 of the tip 3, and the lead holding tube 6 and the strips 11 are forced into the 15 threaded end 4 of the tip, the tight engagement of the strips with the walls of the tip 3 causing the projections 10 on the tube and the threads 4 on the tip to bite into the strips 11 and produce a tight frictional engagement 20 of the strips with the tube and the tip.

For the purpose of ejecting or propelling the lead 9 out of the tube 6 into a writing position, we provide an ejecting rod 12 which is slidably mounted in the tube 6 and 25 is adapted to be actuated by an actuating sleeve 13 threaded for a portion of its length correspondingly to the barrel 1 as indicated at 14 and telescopically received within the end of said barrel opposite the tip 3. The 30 sleeve 13 is formed at an intermediate point in its length with an inwardly pressed rib 15 which serves as a stop for a plug or disk 16 mounted within the sleeve and adapted to engage the end of the ejecting rod 12 as 35 shown in Fig. 1. It will thus be seen that relative revolution of the barrel 2 and the actuating sleeve 13 in one direction will cause relative longitudinal movement of said barrel and sleeve to slide the ejecting rod 40 12 in the tube 6 and eject the lead 9 therefrom, the disk 16 in the actuating sleeve 13 frictionally engaging the end of the ejecting rod 12. The actuating sleeve 13 is 45 prevented from being pulled out of the barrel 2 by engagement of the inner ends of the threaded portions of said barrel and sleeve or in other words the engagement of the threaded portion 14 of the sleeve 13 with the smooth or un- 50 threaded portion at the end of the barrel 1. The portion of the actuating sleeve 13 between the disk 16 and the end of the sleeve opposite its threaded end 14 serves as 55 a chamber to receive the plurality of reserve leads 90 as shown in Fig. 1, the said end of the said chamber being closed by a tubular plug 17 having in one end thereof an eraser 18.

In the ordinary operation of the pencil 60 the actuating sleeve 13 is revolved until its threaded end 14 engages the smooth end of the barrel 2, as shown in Fig. 1, after which a lead is inserted in the outer end of the lead holding tube 6 and pushed inwardly so as to force the ejecting rod 12

against the disk 16. Then with the barrel 2 held in one hand, the sleeve 13 is revolved with the thumb and fingers of the other in a clock-wise direction which causes the same to move inwardly of the barrel 2 to push, through the disk 16, the ejecting rod 12 through the tube 6 and force the lead 9 outwardly of the said tube. If the lead becomes loose in the lead holding tube 6 so that it falls out of the same when held in a vertical position, it is merely necessary to force the tube 6 and the friction strips 11 further into the tip 3 so as to cause a tighter engagement of the tapered end 7 of the tube 6 with the tapered portion 5 of the tip, which action causes the split end of the lead holding tube to tightly engage the lead 9.

Obviously, detail modifications and changes can be made in the construction of our pencil without departing from the spirit or scope of the invention, and therefore we do not desire to be understood as limiting ourselves except as required by the following claims when construed in the light of the prior art.

Having thus described the invention, what we claim is:

1. A pencil including a tubular casing, a lead holding and guiding tube of a size smaller than that of said casing to receive and guide a lead, and complementary strips of frictional material applied to opposite sides of said tube and frictionally engaging the inner walls of said casing to support and hold the tube against movement therein.

2. A pencil including a tubular casing, a lead holding and guiding tube of a size smaller than that of said casing to receive a lead, said tube having exterior projections thereon, and complementary strips of yielding frictional material applied to opposite sides of said tube and frictionally engaging the inner walls of said casing, said projections on the tube being pressed into the said yielding material by the pressure of the engagement of the said yielding material with the walls of the casing, whereby the lead holding tube is securely held in said casing.

3. A pencil including a tubular casing, a lead holding and guiding tube to receive a lead, a pair of substantially cross-sectionally semi-circular strips of yielding frictional material applied to said tube from opposite sides thereof and having an exterior diameter slightly greater than the internal diameter of said casing, said tube and strips being forced into said casing and held by frictional engagement, and means for propelling a lead through said tube.

4. A pencil including a pair of tubular telescoping sections having a threaded engagement whereby relative revolution thereof produces relative longitudinal movement of said sections, one of said sections hav-

ing a lead-guiding passage, an ejecting rod slidably mounted in said passage, a plug fixedly arranged in the other of said sections intermediate the length thereof to frictionally and detachably engage at one side thereof one end of said ejecting rod, the portion of said second-mentioned section at

the other side of said plug serving as a chamber to receive reserve leads, and a closure for said chamber.

LOTHAR W. FABER.
WILLIAM ROBINSON.
